STEAM GENERATOR

Lionel Le Sueur, Addiscombe, East Croydon,
EnglandApplication January 24, 1933, Serial No. 653,328,
and in Great Britain January 12, 1932

3 Claims. (Cl. 122—408)

This invention relates to steam generators and boilers and has reference to devices for preventing priming and for promoting water circulation therein. Generally speaking, baffle devices for this purpose are known but the baffle device of the present invention is of novel form and construction as hereinafter described.

An object therefore of the present invention is to provide a steam generator or boiler with a novel form of baffle device for preventing priming and promoting water circulation.

A further and more specific object is to provide a steam generator or boiler with a submerged baffle device in the form of a plate 15 extended substantially throughout the whole length of the drum but having openings, i. e. apertures or spaces adjacent its ends, or spaces between its ends and the drum ends and also at or near, i. e. in the region of, its longitudinal 20 edges alongside the curved wall of the drum to allow of the escape of steam.

A still further object is to improve the action of water tube boilers, by providing my baffle device in the steam drum thereof in such a position as to cooperate functionally with the water circulation tubes of such boilers. My baffle device is so disposed as to prevent priming and to assist the natural thermo-circulation system by directing the stream of rising hot water (which 30 surges into the drum from the circulation tubes) into a controlled or regulated course and thereby avoid the excessive swirl or turbulence liable to take place in the region of entry of the hot water stream from the circulation tubes, which 35 swirl or turbulence normally prevents the steady and rapid circulation of water within the drum. In combination with the upflowing group of circulation tubes I provide upward extensions reaching to the underside of the baffle plate as 40 hereinafter described.

Another object is to provide a water baffle device of sectional construction in order to facilitate erection and replacement. The sections may be arranged longitudinally side by 45 side in two or more rows or transversely as a single row. Transversely disposed sections can be conveniently formed to be self-supporting, whilst the arrangement of longitudinally disposed sections necessitates the employment of 50 transverse bearers. The disposition, as to height and inclination, of the baffle plate as a whole will naturally vary with the type of boiler and the position of the drum within which it is fitted.

The above objects and such others as are 55 incidental thereto or hereinafter appear will

now be described more fully with reference to the accompanying drawings in which:—

Figure 1 is a longitudinal vertical sectional view illustrative of the steam and water drum of a Babcock water tube boiler showing my 60 baffle plate in position.

Figure 2 is a sectional plan view thereof, and

Figure 3 is a vertical transverse section through the drum of Figure 1.

Figure 4 is a fragmentary plan view illustrative of a modified construction of the baffle.

Figure 5 is a transverse sectional view on the line V—V of Figure 4.

In carrying out the invention, and referring first to Figures 1, 2, and 3, reference numeral 1 70 represents the single substantially horizontal steam drum passing from front to rear of the boiler, 2 the series of rearwardly inclined heater tubes spanning between the front and rear headers which are connected by upflowing circulation tubes 3 and downflowing circulation tubes 4 to the respective ends of the steam drum disposed above.

The baffle plate is constituted by twelve sections 5, longitudinally disposed and arranged in four groups of three. Each of the three rows constituting a group of four sections is supported at opposite ends by transversely disposed bearers 6 which span the drum 1 in chord-like manner. The bearers 6 are conveniently formed of bars of metal with downturned ends 7 which are bolted or otherwise secured to the wall of the drum 1. Each section 5 is strengthened against bending or sagging by a bar 8 (conveniently of half round section) bolted, riveted or welded one on each side of the section upon which it is centrally and longitudinally disposed. At the point of support upon the bearers 6 the sections 5 of one row overlap those of the adjacent row. A longitudinal steam opening 9 is left on each side of the composite plate. The bearers 6 are arranged progressively higher so that the baffle plate as a whole is upwardly inclined from the inflowing circulation tubes 3. Spaces 10 and 11 90 are also left between the ends of the baffle plate and the respective ends of the drum.

In a modified arrangement employing a single row of transversely disposed sections and as shown in Figures 4 and 5, each section 5 is 105 formed with a central gap 15 at each end, so as to form two tongue-like members 16. These members 16 are downturned from about the middle of their length to constitute surfaces 17 for bearing against the wall of the drum 1, whilst 110

leaving a space at each end of the section for the escape of steam.

Each section 5 is furnished with two strengthening bars 8, one at each end thereof, the ends of which bars 8 overlap, if desired, on to the adjacent section 5. If desired a number of sections 5 may be joined together by means of some such strengthening bars 8.

In combination with the baffle plate I use a series of tubular circulators. These circulators or tubes form, as shown in Figure 1, extensions of the customary upflowing circulation tubes 3 from the headers of the boiler to the steam drum and are secured to the underside of the neighbouring baffle section 5. Each tubular circulator consists of a tube 12 which depends into a circulation tube 3, and is provided with an upper flanged portion 13 by means of which it is secured to the underside of the baffle, and the tube 12 is formed with a lip affording an opening 14 for the lateral egress of the hot water passing up from the header, said lipped opening facing the direction of travel of the stream and being under the baffle.

25 What I claim is:—

1. In a multiple water-tube boiler, the combination with a steam drum composed of a circular wall and front and rear ends, of circulation tubes for leading upflowing water to the front end of the drum, circulation tubes for leading downflowing water from the rear end of the drum, a sectionally-assembled flat baffle plate extending submerged substantially throughout the length of the drum but having spaces between its ends and the drum ends and also between its longitudinal edges and the circular wall of the drum, and upward extensions of the upflowing circulation tubes of said drum, said upward extensions having flanged upper ends for attachment to the underside of the baffle plate and having lateral delivery towards the other end of the drum, and said baffle plate as a whole being slightly inclined upwardly from the water inflowing end of the drum to the water outflowing end.

the water inflowing end of the drum to the water outflowing end.

2. In a multiple water-tube boiler, the combination with a steam drum composed of a circular wall and front and rear ends, of circulation tubes for leading upflowing water to the front end of the drum, circulation tubes for leading downflowing water from the rear end of the drum, a flat-baffle plate extending submerged substantially throughout the length of the drum but having spaces between its ends and the drum ends and also between its longitudinal edges and the circular wall of the drum, and upward extensions of the upflowing circulation tubes of said drum, said upward extensions having flanged upper ends for attachment to the underside of the baffle plate and having lateral delivery towards the other end of the drum, and said baffle plate as a whole being slightly inclined upwardly from the water inflowing end of the drum to the water outflowing end.

3. In a multiple water-tube boiler, the combination with a steam drum composed of a circular wall and front and rear ends, of circulation tubes for leading upflowing water to the front end of the drum, circulation tubes for leading downflowing water from the rear end of the drum, a flat baffle plate extending submerged substantially throughout the length of the drum but having spaces between its ends and the drum ends and also between its longitudinal edges and the circular wall of the drum, and upward extensions of the upflowing circulation tubes of said drum, said upward extensions reaching to the underside of the baffle plate and having lateral delivery towards the other end of the drum, and said baffle plate as a whole being slightly inclined upwardly from the water inflowing end of the drum to the water outflowing end.
